GAS COCK

Oscar J. Leins, Milwaukee, Wis., assignor to Milwaukee Gas Specialty Company, Milwaukee, Wis., a Corporation of Wisconsin

Application April 27, 1931. Serial No. 533,197

2 Claims. (Cl. 158—120)

This invention relates to certain new and useful improvements in gas cocks, and refers more particularly to the means for adjusting the area of the outlet or discharge orifice.

5 The means for effecting this adjustment ordinarily includes a member provided with a pointed substantially conical tip, which is known in the art as a "jet plug" and heretofore it has been customary to place this jet plug within the 13 bore of the outlet opening with its tip projected therefrom to cooperate with an opening in a cap threaded onto the outlet of the cock, to, upon movement of the cap toward and away from the jet plug, decrease and increase the area of the 15 opening.

However, it was difficult with this construction to obtain accuracy of adjustment, as the threads by which the cap was mounted were often out of 23 axial alignment with the bore in which the jet plug was disposed so that the tip of the plug would be out of center with respect to the cap opening.

It is, therefore, an object of this invention to 25 provide a novel manner of associating the jet plug with the orifice with which it cooperates so that absolute accuracy is possible.

Another object of this invention resides in the 30 provision of a gas cock structure in which the jet plug is moved toward and away from the orifice with which it cooperates to effect the desired adjustment.

And another object of this invention is to generally improve the construction of gas cocks.

With the above and other objects in view which 35 will appear as the description proceeds, my invention resides in the novel construction, combination and arrangement of parts substantially as hereinafter described and more particularly defined by the appended claims, it being understood that such changes in the precise embodiment of the hereindisclosed invention may be 40 made as come within the scope of the claims.

In the accompanying drawing, I have illustrated 45 one complete example of the physical embodiment of my invention constructed according to the best mode I have so far devised for the practical application of the principles thereof, and in which:

50 Figure 1 is a view partly in section and partly in elevation of a gas cock embodying my invention and illustrating the same associated with a stringer supply pipe, and a mixing manifold;

55 Figure 2 is a cross sectional view taken through Figure 1 on the plane of the line 2—2; and

Figure 3 is a perspective view of the jet plug and the means for adjusting the same, portions thereof being broken away to illustrate structural details.

Referring now more particularly to the accompanying drawing, in which like numerals designate like parts throughout the several views, the numeral 5 represents the body of a gas cock which in the present instance is substantially T shaped and has a longitudinal bore 6 and a transverse 60 tapered bore 7 in its stem. The tapered bore 7 is adapted to receive a tapered valve plug 8 which, by means of a handle 8' may be moved to control the passage of fuel from a supply pipe 9 with which the cock is associated through the longitudinal bore to a transverse bore 10 in the head of the T shaped body, from which it issues through an orifice 11 to be injected into the manifold 12 of a burner, not shown. 65

To obtain maximum efficiency from the fuel, it 70 is desirable to adjust the area of the orifice 11 through which it flows into the mixing manifold 12, and in the present instance this adjustment is obtained in a novel manner assuring absolute accuracy of adjustment. 75

Slidably disposed in the bore 10 is a jet plug 13 having a pointed substantially conical tip 14 adapted to cooperate with the inner peripheral edge of the orifice 11 to, upon movement toward and away from the orifice, adjust the area of 80 the opening and thereby vary the volume of fuel flowing from the orifice. 85

The jet plug 13 is tubular and preferably drawn from a single blank of light stamping material 90 and has a plurality of radially disposed longitudinal webs or ribs 15 on its outer surface which slidably engage the wall of the bore 10 and accurately center the plug with respect thereto and consequently with respect to the orifice 11. The webs or ribs 15 also space the main body of the 95 jet plug from the wall of the bore 10 and thus provide passages through which the fuel flows to the orifice.

Longitudinal movement is imparted to the jet plug by means of an adjusting stem 16 connected with the inner end of the plug, in a manner to be later described, and provided with a threaded head 17 adapted for threaded engagement with an internal thread 18 formed in the end of the bore 10 opposite the orifice 11. A screw slot 19 formed in the extreme outer end of the stem 16 permits the same to be turned to affect longitudinal motion thereof which is imparted to the jet plug through its connection therewith. 105

The connection between the stem and the jet 110

plug permits relative rotational movement between these elements while restricting longitudinal movement therebetween, and comprises a reduced head 20 on the adjacent end of the 5 stem which is disposed within the inner end of the jet plug with the extreme end of the plug abutting a shoulder 21 on the stem 16. The engagement of the end of the plug with the shoulder 21 prevents relative longitudinal movement 10 between the plug and the stem in one direction, and to prevent such movement in the other direction, the wall of the plug is provided with a plurality of inwardly directed projections 22 which engage behind a shoulder 23 formed by 15 reducing the stem inwardly of its head 20.

From the foregoing description, taken in connection with the accompanying drawing, it will be readily apparent to those skilled in the art to which an invention of the character described 20 appertains, that positively accurate adjustment is at all times possible with the device of this invention, for the bore 10 and the orifice 11, being formed in the same member and at the same time positively assures their being in axial alignment and by reason of the snug sliding engagement of the relatively long edges of the plug webs 15 within the inner wall of the bore 10 accurate alignment between the axis of the plug and the orifice 11 to center the conical tip 14 with the 25 orifice is also assured, and inasmuch as the connection between the plug and its adjusting stem has a degree of play, any slight misalignment which may exist between the thread 18 and the bore 10 is accommodated without tending to 30 cause the plug to bind in the bore.

The threaded head 17 closes the outer end of the bore 10 to prevent the passage of fuel therethrough and to positively seal the same and prevent tampering with the adjustment of the jet 40 plug the outer open end of the bore 10 may be closed by a suitable plug 24.

What I claim as my invention is:

1. In a valve, a body having a bore of uniform diameter with a constriction at one end and 45 its opposite end internally threaded, a valve ele-

ment in the bore comprising a cylindrical hollow body having a pointed end adapted to cooperate with the constriction at the end of the bore to meter the flow of fluid therethrough, a plurality of longitudinal fins extending radially from the 80 cylindrical body to slidably engage the wall of the bore and positively center the valve element with respect to the bore and its constriction, said longitudinal fins being at least twice as long as the diameter of the bore so as to have a long contact with the wall of the bore, and means to adjust said valve element in the bore comprising a stem having a freely rotatable connection with the valve element and a threaded head engaged with the internally threaded end portion 85 of the bore.

2. In a valve of the character described, a body having a bore of uniform diameter with a constriction at one end and internally threaded at its opposite end, a valve element disposed within the bore comprising a hollow cylindrical body having one end closed and pointed and its other end open, longitudinal fins extending radially from the cylindrical body to slidably engage the wall of the bore, said fins being at least twice as 100 long as the diameter of the bore to have a long contact with the wall of the bore and thus positively hold the valve element in axial alignment with the constriction whereby the pointed closed end of the element may cooperate accurately therewith to meter the flow of fluid therethrough, and means to adjust said valve element comprising a stem having a reduced end to define an abrupt shoulder, said reduced end projecting 105 into the open end of the cylindrical valve body 110 with the end of the valve body abutting said shoulder, said reduced end of the stem having an annular groove, and projections pressed from the cylindrical wall of the valve into said annular groove to rotatably and non-longitudinally movably connect the stem with the valve element, and a threaded head on the stem engaged with the threaded end portion of the bore.
